CLAIM

The ornamental design for an appliance for preparing beverages, as shown and described.

DESCRIPTION

The patent or application file contains at least one drawing executed in color. Copies of this patent or patent application publication with color drawing(s) will be provided by the Office upon request and payment of the necessary fee.

1. Appliance for preparing beverages

1.1 : Perspective

1.2 : Right

1.3 : Front

1.4 : Bottom

1.5 : Top

1.6 : Left

1.7 : Back

The features covered by a blue overlay in Figures 1.2, 1.3, 1.6 and 1.7 show portions of the bottle with closure that form no part of the claimed design.

1 Claim, 7 Drawing Sheets
(5 of 7 Drawing Sheet(s) Filed in Color)
